UNITED STATES PATENT OFFICE.

PIETER PERDIJK, OF BANDOENG, JAVA.

TRANSITION COUPLING DEVICE.

Application filed September 21, 1925, Serial No. 57,756, and in the Netherlands March 25, 1924.

This invention has for its object to provide a transition coupling device for use with rolling stock and serves to couple an automatic knuckle coupler (M. C. B. car 5 coupler) to another type of automatic or non-automatic car coupler.

For this purpose an auxiliary part (missing link) is fixed by means of ears and bolts at one end of the knuckle and at the other 10 end to the guard arm of the knuckle coupler.

A construction is aimed at by which the compressive and tensile forces are transmitted centrally and regularly to the drawbar head when the transition coupling device is used.

15 The auxiliary part may be easily connected to or disconnected from the nose of the knuckle.

For coupling to a special type of another coupler the auxiliary part is to be shaped in 20 such a form as to suit the other coupler.

A practical form of construction of the present invention will now be described with reference to the accompanying drawings, in 25 which the auxiliary part is shown, fixed to the head of a normal M. C. B. car coupler and coupled to a central automatic hook coupler.

Referring to these vertical drawings: Fig. 1 is a vertical section, Fig. 2 a plan 30 elevation and Fig. 4 a side elevation of the combined couplers. Fig. 3 shows a detail of the construction.

The left sides of the Figs. 1, 2 and 4 show 35 an ordinary, normal construction of the automatic central hook coupler. To the head of its drawbar *a* the hook *b* is pivotally connected by means of a removable pin *c*. The front of the head is formed by the buffer-plate *d*. All these details correspond how- 40 ever to the ordinary construction and need not be altered for the present coupling and therefore they are drawn in thin lines.

The drawbar head *e* of the M. C. B. car 45 coupler, drawn merely in outline, is dealt with similarly as far as the same does not differ from the ordinary constructions. To this nor- 50 mal drawbar head a guard arm having two special ears *f* are cast. Between these ears the auxiliary part *g* is pivotally connected; the other end is fixed to the nose of the knuckle *h* in open position. In carrying out this invention the knuckle is provided with a slot, in which the ear *k* of the auxiliary part is fitted. The knuckle as well as the ear *k*

are vertically connected together by a bolt *m*, in this manner the drawbar head *e*, the auxiliary part *g* and the knuckle *h* practical- 55 ly forming a single part.

If the auxiliary part is made of cast steel, the bufferplate (same as *d*), the drawbar pin *o* (same as *c*) and the hinges can be cast in one single piece as indicated in the drawing. The front *w* of the auxiliary part then serves 60 as the buffer and the cast collar *v* for the transmission of the tensile forces.

Moreover, the auxiliary part has two col- 65 lars *n* and *p* with which the auxiliary part presses against the clutch when under pres- 70 sure. The ear *k* however must have some play and in this way the heavy compressive forces are regularly transmitted to the draw- 75 bar head at the three places *f*, *n* and *p*.

The tensile forces in the standard knuckle coupler pass through the knuckle *h* and are transmitted to the drawbar head *e* merely 75 through the knuckle pin *y*. In the case of coupling the standard coupler to another type of coupler by means of an intermediate link *g* according to the present invention however the tensile forces are carried by 80 the knuckle as well as the ears *f* of the guard arm. The same forces in this case are dis- 85 tributed over the pins *m* (*y*) and *z* with the result that the latter are under less tension than if the knuckle pin *y* were alone em- 90 ployed and so, if need be, the pins *m* and *z* may be thinner and the hole in the nose of 95 the knuckle smaller.

The compression and tensile forces thus being transmitted centrally and regularly 90 the risk of damage to the different parts is less than in the case of using intermediate links, only attached in the slot of the knuckle or to other parts of the drawbar head.

The opening *q* in the arm of the auxiliary part *g* serves for drainage.

If the auxiliary part is removed, the knuckle coupler is immediately capable of being 100 coupled to a standard knuckle coupler as the extra ears *f* at the head of the drawbar and the slot and the hole in the knuckle do not form any obstacle to this.

If there is sufficient space, the auxiliary part used not even to be removed; as it will 105 be sufficient to move it aside, as shown in Fig. 2 in dotted lines. In this position it can be fastened, for instance by means of

a fork r and the pin m . The fork r can be fixed to the drawbar head e and for this purpose the head is to be provided with a flat surface t .

With some carriages the auxiliary part g , as shown in dotted lines in Fig. 2, might strike against other parts and in order to prevent this a specially constructed fork r , a little bit longer than the normal, one, 10 may be employed. A suitable drawbar head may thus be constructed uniformly for the whole rolling stock.

If the knuckle is so constructed that in 15 open position the tail u (as indicated in outlines in Figs. 1 and 2) is situated more in the foreground, the buffer w with the catch ledge v must also be moved in the same direction.

Having now described my invention, what 20 I claim as new and desire to secure by Letters Patent is:

1. A transition coupling device for rolling stock adapted to couple an automatic knuckle coupler to another automatic or 25 non-automatic type of coupler comprising an auxiliary part with one end pivotally connected to the guard arm of the knuckle coupler, means for fixing the opposite end of the auxiliary part to the nose of the 30 knuckle in open position and means whereby the auxiliary part is moved aside when

the knuckle coupler is to be coupled to another one.

2. A transition coupling device for rolling stock adapted to couple an automatic 35 knuckle coupler to an automatic coupler provided with a central hook pivotally connected on a horizontal pin, comprising an auxiliary part with one end pivotally connected to the guard arm of the knuckle coupler, means for fixing the opposite end of the auxiliary part to the nose of the knuckle in open position and means whereby the auxiliary part is moved aside when the knuckle coupler is to be coupled to another 40 one.

3. In a transition coupling device for rolling stock adapted to couple an automatic knuckle coupler to an automatic coupler provided with a central hook pivotally connected on a horizontal pin, an auxiliary part, attached to the front of the knuckle coupler with one end to the guard arm of the knuckle coupler and with the other end to the nose of the knuckle in open position, 50 comprising a catch ledge with which the hook and a buffer with which the buffer of said hook coupler are adapted to engage.

In testimony whereof I have signed my name to this specification.

PIETER PERDIJK.
